UNITED STATES PATENT OFFICE

2,026,069

ENGINE FUEL CONTROL MEANS

Heinrich Schneider, Beloit, Wis., assignor to Fairbanks, Morse & Co., Chicago, Ill., a corporation of Illinois

Application June 29, 1932, Serial No. 619,842

6 Claims. (Cl. 103—41)

This invention relates to improvements in internal combustion engines, and more particularly to improvements in fuel pumps and associated control assemblies used in connection with internal combustion engines of the solid injection type.

An object of the present invention is to provide an improved fuel pump assembly which includes an engine driven cam shaft arranged to reciprocate a cam follower and associated fuel pump plunger which operates in a fuel pump chamber, the chamber being provided with automatically actuated suction and discharge valves, and means associated with the cam follower for varying the timing of the stroke of the fuel pump with respect to the crank position of the engine, by adjustably moving the pump actuating cam follower transversely of a longitudinal axis of the cam shaft.

A further object is to provide an improved fuel pump for an internal combustion engine, the fuel pump including a cam actuated pump plunger, means for varying the timing of the pump plunger stroke with respect to the crank position of the engine, the fuel pump plunger being arranged to reciprocate in a fuel pump displacement chamber which is provided with automatically actuated suction and discharge valves; a by-pass valve arranged to be concurrently actuated with the pump plunger and disposed between the pump chamber and the suction side of the pump, and means associated with the by-pass valve for regulating the effective fuel charge delivered by the fuel pump to the engine cylinder.

A still further object is to provide an improved fuel pump assembly operatively associated with an internal combustion engine, an engine driven fuel pump operating shaft provided with cams which are arranged respectively to actuate pivoted cam followers operatively associated with a pump plunger which is arranged to reciprocate within a fuel pump displacement chamber provided with automatically actuated suction and discharge valves, a cutoff valve arranged to be actuated by the fuel pump operating shaft, means associated with the cutoff valve for automatically controlling the effective fuel charge delivered by the fuel pump responsive to engine speed, a housing for enclosing the fuel pump assembly, and means, externally of the housing and operatively associated with the cam follower assembly, for varying the timing of the fuel pump stroke with respect to the crank position of the engine.

An additional object is to provide an improved fuel pump assembly which includes cam actuated mechanism for actuating a fuel pump plunger disposed within a fuel displacement cylinder, automatically actuated suction and discharge valves associated with the cylinder, a bypass valve associated with the cylinder, and arranged to be actuated by the cam mechanism, a governor mechanism for controlling the bypass valve, a housing for enclosing the fuel pump assembly and associated control mechanism, and means actuated from the exterior of the housing for adjusting the controlling movement of the governor mechanism.

An additional object is to provide an improved fuel pump assembly for internal combustion engines, which is neat and compact in arrangement and is inexpensive to construct and maintain.

Further objects and advantages will appear from the following detailed description of parts and from the accompanying drawings, in which:

Fig. 1 is a longitudinal sectional elevation of a preferred form of fuel pump assembly, taken along lines 1—1 in Figs. 3 and 5; Fig. 2 is a sectional elevation taken along lines 2—2 in Figs. 25 3 and 5; Fig. 3 is a section taken along line 3—3 in Figs. 1 and 2; Fig. 4 is a section, partially in elevation, taken along line 4—4 in Fig. 2; Fig. 5 is a section taken along line 5—5 in Fig. 2; and Fig. 6 is a fragmentary section taken along line 6—6 in Fig. 2.

Referring to the drawings, the numeral 10 designates, generally, a housing for enclosing and supporting the fuel pump assembly which includes a fuel pump operating shaft 11 suitably journaled in ball bearings 12 carried in wall portions of the housing. This shaft is, by preference, provided with spaced cams 13 which may be formed integrally with the shaft. It will, of course, be understood that the cam shaft 11 is 40 operatively connected to and driven in timed relation by the crank shaft (not shown) of an internal combustion engine. The cams 13 are arranged operatively to engage, respectively, associated cam followers or rollers 14 which are 45 carried, respectively, on pins 15 suitably journaled in connecting links 16. Reciprocating movement of the cam follower 14 is transmitted through the link 16 to a crosshead member 17 which is provided, by preference, with a recessed portion 18 for receiving a round ended portion 19 of the link 16. Each crosshead member 17 is, by preference, arranged to reciprocate, respectively, in guideways 20 provided in a partition 21 which is formed integrally with the 55

housing 10. As shown in Fig. 3, an upper end portion 22 of the crosshead member 17 operatively engages an end portion of a fuel pump plunger 23 which is arranged to be reciprocated within a fuel displacement cylinder 24 formed in a pump barrel 25, the pump plunger being maintained in contact with the end portion 22 of the crosshead by means of a spring 26. This spring, acting through the pump plunger 23, crosshead 17, link 16 and pins 15, urges the cam roller 14 into engagement with the operative surface of the cam 13.

In the preferred example, four individual pump barrel assemblies are, by preference, disposed in a row, and are removably secured to a block or body member 27 which is secured by means of cap screws 28 to the housing 10. The pump barrel 25 is secured to the block member 27 by means of a threaded bushing member 29 which also serves as an end abutment for the spring 26. The cylinder portion 24 of the pump is, by preference, in fluid communication with a passage or conduit 30 formed transversely of the block member 27, this passage being, at times, in fluid communication with the fuel supply reservoir 31 which is disposed longitudinally of the block member 27, and serves as the common supply source for all the individual pump assemblies. The passage of fuel from the supply source 31 to each individual pump cylinder is controlled by an automatically actuated suction valve 32, one of which is provided for each fuel pump assembly. As the fuel is compressed within the cylinder 24 by actuation of the pump plunger which it will be noted is of substantially constant stroke, the compressed fuel is discharged through the passage 30, and thence through an automatically actuated spring loaded discharge valve 33 which controls the discharge of fuel into a conduit 34 connected, by preference, to an injection nozzle (not shown) associated with the combustion chamber of an internal combustion engine. The timing of the fuel pump plunger actuation by the cam shaft, with respect to the crank position of the engine, may be varied by the mechanism hereinafter described.

An eccentric shaft 35 is, by preference, spaced above and parallel to the cam shaft 11, the end portions of the shaft being suitably journaled in bearings carried in wall portions of the housing 10. A plurality of rocker arms 36 are carried on the eccentric shaft 35, each rocker arm being connected with its associated cam follower assembly 14 by means of the pins 15. By partial rotation of the eccentric shaft 35, the cam follower 14 may be moved transversely of the longitudinal axis of the shaft 11 for adjustably positioning the roller 14 with respect to the cam 13. Partial rotation of the eccentric shaft 35 may be effected from the exterior of the housing 10 by means of a manually controlled lever 37 which is operatively connected to an end portion 38 of the shaft 35 which extends through and is journaled in a wall portion of the housing 10. This lever is, by preference, provided with a spring pressed member 39 which is arranged to engage, selectively, a plurality of notched portions 40 formed in a casing 41 which is removably secured to an end portion of the housing 10. By urging the spring pressed member 39 out of register with any particular notch 40, the lever may then be manually actuated so as to rotate the eccentric shaft 35 to move the rocker arms 36, with their associated cam

followers 14, transversely of the cam shaft 11. Such a control movement varies the time relation of the individual fuel pumps with respect to the crank position of the engine, and once the proper timing has been determined, the spring pressed member 39 of the manual control lever may be released and locked into engagement so as to maintain the eccentric shaft in adjusted timed position. It will be readily seen that the entire timing control movement is effected from the exterior of the housing 10; suitable indicia may be provided upon the casing 41 for visibly indicating the adjusted timed setting. Further, this control movement varies the timing of the fuel pump stroke, with respect to the crank position of the engine, but does not appreciably affect the fuel charge delivered by the fuel pump which is supplied by an independently adjustable charge controlling mechanism hereinafter described.

The quantity or charge of fuel delivered by the fuel pump is controlled by the time operation of a cylindrical by-pass or cut-off valve 42 which is, by preference, arranged to reciprocate in a valve bore 43 formed in a valve body 44 which is removably secured to the block member 27. This cut-off valve is arranged to control a port 45 which is in fluid communication with the passage 30 and fuel pump chamber by means of a conduit 46 formed in the body member 27. When the port 45 is uncovered by the piston control valve 42, near the end of the compression stroke of the pump plunger, the compressed fluid within the passage 30 is bypassed through the port 45, bore 43, and then through passages or conduits 47 and 48, the latter conduit being in fluid communication with the fuel supply reservoir 31. The conduit 47 is, by preference, formed within the body member 27, and connects all the individual valve piston bores 43 of the fuel pumps with the fuel supply reservoir 31 through the single passage 48. It will be apparent that proper timing of the cut-off valve 42 with respect to the port 45, and the position of the pump plunger with respect to its pump stroke, control the effective fuel charge delivered by the pump to its associated cylinder. Timed actuation of the piston valve is effected by means of the cam 13, crosshead member 17 and associated parts, and thence through a rocker member 49 which is pivoted intermediate its ends on an eccentric shaft 50 suitably supported in wall portions of the housing 10. This eccentric shaft serves as a shiftable fulcrum for the rocker arm for controlling the stroke of the cut-off valve plunger. An end portion of the rocker arm is, by preference, operatively connected to a link 51 which is pivotally connected to an end portion 52 of the piston valve 42. The opposite end of the rocker arm 49 is, by preference, provided with a portion 53 which slidably engages a slotted portion 54 formed in a spherical member 55 which is supported in a socket formed in the crosshead member 17. As the crosshead member 17, with its associated parts, is reciprocated by the cam shaft 11, the rocker arm is oscillated to reciprocate the piston valve 42 with respect to its valve bore. Therefore, it will be readily seen that as the pump plunger is being urged inwardly, or on its compression stroke, the cutoff valve 42 will, through the rocker arm connection to the crosshead 17, be moved toward the port opening position, and that when the port 45 is uncovered the effective fuel delivery 75

stroke of the fuel pump plunger is completed. An annular chamber 56 is, by preference, provided about the cut-off valve 42 in fluid communication with the port 45 so as to equalize and distribute the fuel pressure about the peripheral surface of the cut-off valve 42 whereby to balance the valve within the bore 43. The cut-off point of the cut-off valve with respect to the position of the pump plunger in the pump stroke may be automatically controlled in response to the speed of the engine, and thereby control the effective fuel charge that is being delivered to the engine cylinder.

For effecting automatic control of the cut-off valve 42, the eccentric shaft 50 is operatively connected to a governor generally indicated at 57, which is mounted within a housing or casing 58 detachably secured to a wall portion of the housing 10. An end portion 59 of the cam shaft 11 projects into the interior of the governor casing 58, the cam shaft being, by preference, connected by means of a suitable coupling member 60 to a shaft extension 61 which is suitably journaled in a bearing 62 carried by the casing 58. A spiral gear 63 is, by preference, carried on a sleeve 64 which is secured to the shaft extension 61, the sleeve being provided with an annular beveled portion 65. A corresponding beveled portion formed on the spiral gear 63 is urged by means of a spring 66 into engagement with the beveled portion on the sleeve, the spring 66 being disposed between the flanged portion formed on the coupling and the lateral face of the spiral gear. Rotation of the cam shaft is transmitted through the spiral gear 63 to a meshing gear 67 which is suitably secured to a shaft 68 journaled in suitable bearings 69 supported by the housing 58. Weighted members 70 are, by preference, pivotally connected by means of pins 71 to a carrier member 72 which is suitably secured to the shaft 68. It will be readily seen that rotation of the shaft 68 causes outward movement of the weighted members 70, responsive to increase in engine speed to cause an endwise movement of the inner ends 73 of the weighted arms 70. These end portions of the arms 70 engage an annular channelled portion 74 which is provided on a governor spindle 75, carried loosely on the shaft, and being arranged to be moved endwise of the shaft under the influence of the centrifugal action of the governor weighted arms 70. This endwise movement is imparted to an annular member 76 which is, by preference, carried on a roller bearing 77 supported on an end portion of the endwise movable governor spindle 75, the member 76 being provided with diametrically opposed trunnion portions 78 to which are pivotally connected links 79. The opposite end of each link 79 is, by preference, connected by means of a pin 80 to an intermediate portion of a rocker arm 81, which is pivotally connected by means of a pin 82 to the governor casing. It will be seen in Fig. 5 that clockwise movement of the arm 81 is opposed by springs 83 which are attached, respectively, to lever members 84 pivotally connected by means of pin 80 to the arm 81, and that the lever members are fulcrumed on movable rollers 85 which are carried by means of pins 86 attached to a fulcrum carrier structure 87. The opposite ends of the springs 83 are each connected to a pin 88 which is carried by the casing for the governor.

Variable spring loading is effected by changing the position of the fulcrum with respect to the

end portions of the lever, by manual rotation of a hand wheel 89 which is secured to a projecting portion of a shaft 90 supported by and extending through the governor casing. This shaft is, by preference, provided with a threaded portion 91 which operatively engages a correspondingly threaded portion provided in the carrier structure 87. Manual rotation of the shaft 90 produces endwise movement of the fulcrum carrier structure for effecting a variable fulcrum 5 positioning or loading of the springs 83. The setting of the fulcrum is visible from the exterior of the casing by means of a pointer 91 which is associated with a suitable scale formed on the outer wall of the case. This pointer is operatively connected to the traveling nut portion of the fulcrum carried by means of a crank and pin connection 92. The control movement of the governor spindle is transmitted to the rocker arm 81, and thence to a link 93 which is pivotally connected to the rocker arm 81 by means of a pin 94, and to a crank arm 95 which is secured to an end portion 96 of the eccentric shaft 50, Fig. 6. Control movement of the governor is transmitted through the above described mechanism to cause a partial rotation of the eccentric shaft 50 which results in effective control of the movement of the cut-off valve 42 for regulating the fuel discharge delivered by the fuel pump responsively to the speed of the engine. 30

To provide manual control of the eccentric shaft 50 and cut-off valve 42, the end portion of the eccentric shaft is extended beyond the wall portion of the casing 10, a collar member 97 being secured to the extended portion of the eccentric shaft. This collar member is, by preference, provided with a projecting lug portion 98. The manual control lever 99 is, by preference, suitably mounted on a stud shaft 100 which is carried by the casing 41. A pin 101 is secured 40 to the lever 99 in such a manner that a portion thereof projects transversely of the collar member 97 and into the path of movement of the lug 98. This manual control lever is, by preference, provided with a cylindrical bore 102 for 45 receiving a plunger member 103 which is urged outwardly by means of a spring 104 to selectively engage notches 105 or 106 formed in the casing 41. This plunger is secured to a handle portion 107 which fits over the bore portion of the lever, so that by drawing the handle outwardly the plunger 103 may be removed from the notch 50 engaged and the handle moved angularly for adjusting movement. With the manual control lever in the position shown in Fig. 4, the pin 101 is angularly spaced from the lug portion 98 on the collar 97 sufficiently to permit appreciable control movement of the eccentric shaft 50 under the influence of the governor. Now when the lever 99 is moved counterclockwise, Fig. 4, the pin 101 engages the projecting lug 98 to rotate the eccentric shaft 50 and collar member 97 sufficiently to permit the spring pressed member 103 to engage a notch 106 formed in the casing 55 41. In this position the manual control lever is locked in position. Such a positioning of the manual control lever results in an adjustment of the stroke of the cut-off valve 42 whereby the fuel charge is by-passed at a point in the 60 pump plunger stroke so that no fuel is delivered to the injection nozzles, the adjustment resulting in an insufficient pressure within the displacement chamber to actuate the discharge valve 33.

Provision is made for preventing admixture of the fuel oil with the lubricating oil by separating the pump housing into a pair of independent compartments 108 and 109, by means of the partition 21. The compartment 108, disposed beneath the partition, is provided with a sufficient quantity of lubricating oil 110 for splash oiling the mechanism contained therein, the lubricating oil being maintained at a level 111 by means of an overflow conduit 112 or the equivalent, any suitable means being provided to supply lubricant to this chamber. This lubricating oil is confined within the compartment 108, and is separated from the compartment 109 which 10 serves to catch fuel oil drip from the pump assembly. In order to prevent fuel oil from seeping down the crosshead guideways, and into the compartment 108 to mix with the lubricant oil therein, the crosshead members are each provided with suitable drip arrestors 113 which direct the fuel oil into the chamber 109. Suitable means (not shown) may be provided for draining the drip fuel oil accumulating in the compartment 109 back to the fuel reservoir or any other suitable receptacle.

It will, of course, be understood that the present detailed description of parts and the accompanying drawings relate only to a single preferred embodiment of the invention, and that 30 substantial changes may be made in the described arrangement and construction of parts without departing from the spirit and full intended scope of the invention, as defined in the appended claims.

I claim:

1. In an injection pump assembly for solid injection engines, a pump body or block having a bore therethrough constituting a displacement chamber therein, a pair of spaced bored passages arranged in parallel relation so as to intersect the first said bore, a pump plunger in one of said bored passages, a by-pass plunger in the other bored passage, the plungers being adapted for reciprocal movement into spaced portions of 40 said displacement chamber, an intermediate bored passage transverse to and communicating with the first said bore, an inlet valve and a discharge valve each of automatic type, disposed in alignment in said intermediate bore between said plungers, a fuel supply conduit formed in the block and extended at an angle from one end of said intermediate passage, a by-pass conduit formed in the block, and extended at an angle from the opposite end of one of said parallel 50 passages, a duct formed in the block connecting said conduits, means for operating said pump plunger, and means operatively connecting the by-pass plunger to the pump plunger for positive actuation of the latter plunger in each direction, the last means including an element between the plungers, for controlling their operative relation.

2. In an injection pump assembly for multi-cylinder solid injection engines, including a pump body for a plurality of pumps, and provided, for each pump, with a bore forming a displacement chamber therein, a constant-stroke plunger disposed transversely of and operable adjacent one end of said chamber, a second bore 65 for each pump unit, located transversely and intermediate the ends of the displacement chamber, inlet and discharge valves of automatic type in controlling relation to said chamber and disposed in said second bore, a by-pass duct within said pump body, serving to connect the several

displacement chambers to a source of fuel supply, a slideable plunger in each pump unit, serving as a cutoff valve for controlling communication between the associated displacement chamber and said by-pass, the cut-off valve being disposed adjacent the opposite end of the displacement chamber, a fuel supply duct formed in the pump body, and common to the several pump units, a conduit connecting the supply duct and by-pass duct, a rocker for each pump unit, for 10 actuating each cutoff valve responsive to movement of the associated plunger, an eccentric fulcrum shaft common to said rockers, and control means operatively associated with said eccentric fulcrum.

3. An injection pump and fuel control assembly for internal combustion engines, including a housing, a pump body for a plurality of pumps carried by said housing, and including a displacement chamber for each of the several 20 pumps, individual pump plungers operating in said displacement chambers, a cam and cam-follower assembly for actuating each of said plungers, a mechanically actuated cutoff valve for each displacement chamber, arranged parallel to and spaced from the associated plunger, a rocker disposed substantially between and operatively interconnecting each of the said plungers and its associated cutoff valve, intake and discharge valves in each displacement chamber, 30 between the plunger and cutoff valve, an eccentric control shaft common to the several rockers, an intake conduit formed in the pump body, common to the several intake valves, a by-pass conduit formed in the pump body, common to 35 the several cut-off valves, and a conduit formed by the pump body, interconnecting the said by-pass and intake conduits.

4. In an injection pump assembly for solid injection engines, a pump body or block having a displacement chamber therein, a pair of plungers arranged in parallel relation, and adapted for reciprocal movement into spaced portions of said displacement chamber, an inlet valve and a discharge valve each of automatic type, disposed in line with each other in said chamber intermediate said plungers, an oil supply passage in the block, leading to the inlet valve, an overflow passage in the block, controlled by one of said plungers, a conduit in the block, between said passages, a rocker disposed below the pump body, between said plungers and pivotally connected at one end to one of said plungers, an element rockably carried by the other plunger and slidably receiving the other end of the rocker, an eccentric fulcrum for said rocker, disposed substantially between said plungers, and means for rotating said eccentric, to shift the fulcrum of said rocker.

5. An injection pump assembly for solid injection engines, including a fuel pump of a type embodying spaced displacement and cut-off plungers, a pump body or block in which the plungers operate, means for actuating the displacement plunger, a rocker connecting the displacement and cut-off plungers, an eccentric fulcrum shaft constituting a pivot for said rocker, and extending between the ends of the rocker and between said plungers, the shaft projecting from each end of the pump block, the displacement plunger including a crosshead, a bushing rockably carried by the crosshead and slidably receiving one end of the rocker, a governor at one end of the block, an angularly adjustable control connection by which the gover- 71

nor is operatively related to the adjacent projecting end of the fulcrum shaft, a manual control lever pivotally mounted near the opposite end of the block and shaft, and a lost-motion connection between the shaft and manual control lever, adapted to permit normal governor control of the shaft independently of movement of the manual control lever, the connection including an arm or projection adjustably secured to the control end of the shaft, and a companion, abutting projection carried by the lever.

6. An injection pump assembly for solid injection engines including, in combination with a fuel pump embodying spaced displacement and cut-off plungers, means for actuating the displacement plunger, a rocker operatively connecting the plungers, an eccentric fulcrum shaft providing a pivot for said rocker between its ends, and between the said plungers, a cross-head carried by the displacement plunger, a

bushing for slidably receiving one end of the rocker, and adapted for oscillation in the cross head, a governor at one end of said shaft beyond the pump, an arm adjustably carried by said end of the shaft, to which the governor is operatively connected, a pivoted manual control lever disposed at the opposite end of the pump, a projection carried by said lever and a projection carried by said shaft, the projections adapted to be brought into abutting relation for manual actuation of said shaft to an extreme position, the projections being normally angularly displaced, whereby to permit normal governor control of the shaft, free of movement of the manual control lever, and a collar element adjustably secured to said eccentric fulcrum shaft, the shaft-mounted projection being carried by said collar element.

HEINRICH SCHNEIDER.

20
